UNITED STATES PATENT OFFICE

HERMAN MILLER, OF CHICAGO, ILLINOIS, ASSIGNOR TO BURRELL ENGINEERING & CONSTRUCTION COMPANY, OF CHICAGO, ILLINOIS, A CORPORATION OF ILLINOIS

OIL BURNER

Application filed July 23, 1929. Serial No. 380,301.

This invention relates to oil burners and an object of the invention is the provision of improved means for feeding fuel oil from the source of supply to the atomizer and also 5 the provision of improved atomizing means.

A further object of the invention is the provision of a rotary atomizing device in an oil burner constructed and arranged in conjunction with the air supply to utilize the vacuum 10 um created by the forced air discharge as an instrumentality to cooperate and assist both in extracting oil or an oil mixture from the atomizer and in producing a more complete and efficient atomizing.

15 A further object is the provision of improved mechanism of comparatively simple, yet efficient construction for the oil supply, air supply and atomizing operations which includes the production of an air blast for 20 combustion and mixing purposes in the form of a hollow cylinder surrounding oil supply mechanism adapted to convey oil to the column of forced air both by centrifugal action and through the vacuum created in the vortex 25 of the air column. These and other objects are accomplished by transporting the oil in liquid form in close proximity to the point of atomization where the vacuum action of the forced air supply serves to withdraw oil 30 from the atomizer and thus produce a more thorough and efficient mixing or atomization.

35 A further object is the provision of an improved rotary atomizer having means for utilizing a portion of the forced air current on each side of the atomizer discharge opening, whereby a secondary current of forced air is utilized and a vacuum suction action provided in close proximity to the oil discharge opening of the atomizer, in addition 40 to the principal vacuum action created by the forced air current which surrounds the entire atomizing device.

45 Other objects will appear hereinafter.

The invention consists in the combinations and arrangements of parts hereinafter described and claimed.

The invention will be best understood by reference to the accompanying drawings forming a part of this specification, and in 50 which:

Fig. 1 is an elevational view taken on the right side of the oil burner showing the burner in association with the fire box of a furnace, the latter being shown in longitudinal section;

Fig. 2 is a rear elevational view, partly in section, of the air fan or blower;

Fig. 3 is a front elevational view of the atomizer employed in carrying out the invention, with the front disk plate partially 60 broken away to show the air vanes;

Fig. 4 is a longitudinal sectional view of the atomizer taken on the line 4—4 of Fig. 3;

Fig. 5 is a transverse sectional view taken 65 on the line 5—5 of Fig. 4;

Fig. 6 is an enlarged transverse sectional view, with the electric motor omitted, taken substantially on the line 6—6 of Fig. 1;

Fig. 7 is a longitudinal vertical sectional view taken on the line 7—7 of Fig. 6;

Fig. 8 is a side elevational view of the air intake adjusting sleeve;

Fig. 9 is a longitudinal sectional view of the air intake adjusting sleeve, detached 75 from the apparatus;

Fig. 10 is a detailed view of the oil discharge pipe centering plate;

Fig. 11 is a transverse sectional view taken substantially on the line 11—11 of Fig. 7; and

Fig. 12 is an interior elevational view of 80 the front fan housing member, partly broken away to show the interior construction.

The oil burner with which the present invention is associated, comprises a base member 15 supported by internally threaded 85 blocks 16 adapted to receive threaded adjusting rods 17 by means of which base member is engaged for vertical adjustment by adjusting nuts 18. Extending upwardly from the base member 15 is a plurality of supporting legs 19 which are adapted to support an upper table upon which is mounted the operating electric motor 20. For the purposes of the present disclosure, certain dimensions, ratios, etc., will be embodied for designating 90 a representative installation, although it is to be understood that the invention is not restricted thereto. The motor preferably has a normal operating speed of 1750 revolutions per minute, and upon the shaft 21 is keyed 100

drive pulley 22 connected by belt 23 to pulley 24 keyed upon hollow rotary shaft 25. Pulley 22 is preferably twice the diameter of pulley 24 whereby hollow shaft 25 is given a normal operating speed of 3500 revolutions per minute in a typical installation. Integrally formed upon pulley 24 is a second pulley 26 connected by belt 27 to pulley 28 which is connected to shaft 29 and adapted to drive oil pump 30. The oil pump 30 may be of any standard improved type and is employed for the purpose of exerting a comparatively low pressure in the neighborhood of 5 pounds for forcing oil to the metering valve, hereinafter referred to. In certain installations where the oil supply tanks are so disposed as to furnish sufficient force by gravity, oil pump 30 may be dispensed with. The main oil supply is carried to the apparatus by pipe 31 leading to a standard filtering device 32. The oil is conveyed from the filtering device 32 through pipes 33 and 34 to the oil pump 30 and thence through the oil feed line 35 to the metering valve 36. The metering valve 36 is of standard construction and is adapted to be manually adjusted for regulating the oil supply to the atomizer. Electric current for motor 20 is furnished by wires in cable 37 leading from a standard relay box 38 operatively associated with thermostatic control mechanism which is not shown nor described in detail because not forming a part of the present invention. A second cable 39 contains electric wires leading to an automatic electrical controlled oil shut-off valve 40. After passing the metering valve 36 the oil supply is carried through pipe 41 which is connected by elbow 42 to a centering plate 43. Plate 43 is provided with a central opening, and a relatively smaller oil discharge pipe 44 is connected thereto by means of threaded adjusting plugs 45, 46, whereby the oil supply has a continuous flow from the metering valve 36 through the oil discharge pipe 44. Discharge pipe 44, in a representative installation, has an outside diameter of approximately $\frac{1}{4}$ inch and a slight clearance is provided between the outside periphery of discharge pipe 44 and the internal bore of hollow shaft 25. In the device illustrated, a satisfactory clearance at this point is approximately $\frac{1}{16}$ inch. It is further desirable to maintain pipe 44 centrally disposed within the hollow shaft 25 particularly inasmuch as pipe 44 has no support in advance of centering plate 43, and for this purpose plate 43 has threaded therein three adjusting screw bolts 47 equally spaced, the ends of which bear against a supporting web 48 formed between the forward legs 19. Plate 43 is clamped to web 48 by bolts 49 disposed within slots 50, and thus for a centering operation bolts 49 are loosened, screw bolts 47 adjusted to properly

center feed pipe 44, and bolts 49 are then tightened in place. The forward end of hollow shaft 25 is externally threaded to receive an atomizer 51 which, as shown in Fig. 4, consists of an inner shell portion 52 providing an oil receiving chamber 53. Disposed radially on the outer periphery of shell 52, preferably at points adjacent the discharge end of discharge pipe 44, are a plurality, six in the present embodiment, of connecting bosses 54, each of which is provided with a central oil opening 55 communicating with a hollow cylindrically shaped oil discharge chamber 56, formed between an intermediate tubular member 57, supported by bosses 54 and an outer tubular member 58. As shown in Fig. 4, tubular members 57 and 58 are spaced to provide a circular oil discharge opening 59 at their forward extremities, but are sealed together at the rear extremity. Disposed at the rear extremity of member 58 is a rearwardly and outwardly flared flange 60 which acts as a baffle or guide for diverting a portion of the forced air supply through air passage 61 in addition to the air supply forced between the air projector and the atomizer, as hereinafter described. It is also desired to provide a device of an air turbine type at the forward end of the inner shell portion 52, which consists of a disk 62 connected to the shell 52 by a plurality of radially extending vanes 63 and having a central opening 64 for receiving air which is discharged outwardly by a centrifugal and turbine action to a point in proximity to the oil discharge opening 59. In order to provide proportionately adequate oil outlet openings relative to the oil discharge opening, the combined cross-sectional area of the six ports 55 is equal to approximately three times the cross-sectional area of the bore of the oil discharge pipe 44, the diameter of which, in the installation illustrated, is $\frac{3}{16}$ inch.

Shaft 25 is supported in bearings 65 and lubrication is preferably afforded by absorbent textile material or wool disposed in pockets 66. The absorbent lubricant material extends into an oil or lubricant chamber 67 to which lubricant is supplied by pipe 68 and filler cap 69. Bearing or bushing members 65 are mounted in a rear fan housing member 70 supported by legs 71 extending downwardly to base member 15. The rear hub portion of housing member 70 is provided with a plurality of air intake ports 72 which are adapted to adjustably register with corresponding openings 73 provided upon the air intake adjusting sleeve 74 whereby upon rotation of the latter the volume of air intake may be controlled, being secured in adjusted position by screw bolt 75.

Formed integrally with the rear fan housing 70 is an upper table 76 which serves as a support for the oil pump 30. Keyed upon

shaft 25 is a fan 77 preferably of the turbine type having a forward imperforate plate 78 and a rear spaced plate 79 joined by a plurality of comparatively long vanes 80 and alternating short vanes 81. Plate 79 is spaced from the central bearing support portion of the rear fan housing to provide a circular air inlet 82, and disposed in advance of fan plate 78 is a stationary imperforate plate 83 formed integrally with the front fan housing member 84, and connected thereto by a plurality of radially extending vanes 85. Thus, upon rotation of the fan air is drawn through the air intake ports 72, and is then carried outwardly through the fan and thence forced inwardly between vanes 85 through the front fan housing member 84. Bolted upon the forward edge of the front fan housing member 84 is a projector 86 which is gradually reduced to terminate in a forward circular edge portion 87 forming a circular air space 88 which, in the present embodiment illustrated, provides a space approximately $\frac{1}{16}$ inch in width encircling the atomizer 51. The respective pulleys are preferably all enclosed within a pulley housing 89.

In operation oil is carried through the oil supply pipe 44 in accordance with the adjustment of the metering valve 36, and normally is discharged in liquid form into chamber 53 of the atomizer 51. Simultaneously, the forced current of air supply is divided by baffle 60 preferably in such proportion that approximately 30% of the volume of air passes through air passage 61 and approximately 70% is forced between the circular opening 88 provided between the circular projector edge 87 and the outer tubular sleeve member 58 of the atomizer 51. These two currents of air each are in the form of a hollow cylinder and are swirling in motion by reason of the speed of the fan and the relatively high rotary speed of the atomizer. The two currents which pass through openings 61 and 88, respectively, create a vacuum action between them which serves to form a suction directly upon the oil discharge circular opening 59, and in addition a vacuum effect is created causing additional suction upon the oil discharge opening by reason of these combined currents of air in advance of the atomizer. In other words, there is a primary vacuum created by the entire air discharge in advance of the atomizer, and a secondary lesser vacuum created where the two currents of air meet adjacent the oil discharge opening. This general vacuum action also induces a current of air to be carried through the opening 90 between pipe 44 and shaft 25, which action is enhanced by the relative motion of the shaft, and therefore, as the oil drips into chamber 53 a preliminary oil and air mixing operation takes place due to the air carried through passageway 90. The combined centrifugal action of the atomizer

and the vacuum action created by the air supply carries this preliminary mixture through the plurality of openings 55.

A higher degree of efficiency is obtained by the provision of the fan device at the advance end of the atomizer which has a tendency to throw air outwardly where the oil discharge takes place and thus spread the mixture directly in advance of the atomizer. After passing through ports 55 the oil is deposited in the form of a film in the space between tubular members 57 and 58, after which the oil is drawn through circular opening 59 by the vacuum action above described. It will thus be seen that there is no interruption or mechanism tending to impede or disrupt either the uniform column of forced air currents or the uniform supply of oil to the air currents, whereby there is produced a thorough mixing and atomization.

Depending upon the quantity of fuel oil supply, the flame produced upon ignition of this mixture is carried rearwardly in the combustion chamber 91 of a furnace, and preferably the rear wall of a rectangular furnace is provided with a corbelled fire brick construction 92 which tends to throw the flame backwardly, and such particles of the atomized oil as are not consumed in the initial burning are consumed by this return action of the flame. However, it will be understood that interior fire brick linings of the furnace or heating plant to which the apparatus is connected may be varied to suit different conditions. Under normal operating conditions atomization is so perfected that complete combustion takes place and maximum heating value of the fuel oil is utilized. For ignition purposes a gas pilot light 93 is preferably provided, having a control valve for increasing the length of the pilot jet when the apparatus is started and proper conditions for igniting the mixture reached. The nozzle of the projector 86 is extended a slight distance within the combustion chamber 91 of the heating plant as shown in Fig. 1, and is extended through a plate 94 hermetically sealed in the clinker door opening or fire or ash door opening.

The grades of oil usually employed for oil burner purposes may be satisfactorily used in the present device at a great saving in comparison to the heat generated. Fuel oil of 24-26 or 28-30 degrees Baumé may be satisfactorily employed, and the apparatus will satisfactorily operate with oils of greater density than will many other types of burners.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifi-

cations as come within the scope of the appended claims.

Having thus described my invention, what I claim as new and desire to secure by Letters Patent is:

1. An oil burner comprising, in combination, a hollow rotatably mounted shaft, an oil discharge pipe enclosed within said shaft, power means for rotating said shaft, forced air supply means, an atomizer mounted upon said shaft adjacent the discharge end of said oil discharge pipe, an air projector adapted to confine the forced air and terminating in a circular edge portion spaced from said atomizer to provide a circular air opening, said atomizer provided with an inner tubular member and an outer tubular member with an air passage therebetween, said outer tubular member formed to provide an annular oil discharge opening spaced from said inner tubular member.
2. An oil burner comprising, in combination, a hollow rotatably mounted shaft, an oil discharge pipe enclosed within said shaft, power means for rotating said shaft, forced air supply means, an atomizer mounted upon said shaft adjacent the discharge end of said oil discharge pipe, an air projector adapted to confine the forced air and terminating in a circular edge portion spaced from said atomizer to provide a circular air opening, means mounted upon the extreme advance end of said atomizer for creating an outward current of air, said atomizer provided with an inner tubular member and an outer tubular member with an air passage therebetween, said outer tubular member formed to provide an annular oil discharge opening spaced from said inner tubular member.
3. An oil burner comprising, in combination, a hollow rotatably mounted shaft, an oil discharge pipe enclosed within said shaft, means for adjustably centering said oil discharge pipe within said shaft, power means for rotating said shaft, forced air supply means, an atomizer mounted upon said shaft adjacent the discharge end of said oil discharge pipe, an air projector adapted to confine the forced air and terminating in a circular edge portion spaced from said atomizer to provide a circular air opening, said atomizer provided with an inner tubular member and an outer tubular member with an air passage therebetween, said outer tubular member formed to provide an annular oil discharge opening spaced from said inner tubular member.
4. An oil burner comprising, in combination, a hollow rotatably mounted shaft, an oil discharge pipe enclosed within said shaft, means for adjustably centering said oil discharge pipe within said shaft, power means for rotating said shaft, forced air supply means, an atomizer mounted upon said shaft adjacent the discharge end of said oil dis-

charge pipe, an air projector adapted to confine the forced air and terminating in a circular edge portion spaced from said atomizer to provide a circular air opening, said atomizer provided with an inner tubular member and an outer tubular member with an air passage therebetween, said outer tubular member formed to provide an annular oil discharge opening spaced from said inner tubular member.

5. An oil burner comprising, in combination, a hollow rotatably mounted shaft, an oil discharge pipe enclosed within said shaft, power means for rotating said shaft, forced air supply means, an atomizer mounted upon said shaft adjacent the discharge end of said oil discharge pipe, an air projector adapted to confine the forced air and terminating in a circular edge portion spaced from said atomizer to provide a circular air opening, said atomizer provided with an inner tubular member and an outer tubular member with an air passage therebetween, whereby the forced air current is adapted to create an oil extracting air suction in advance of said atomizer, said outer tubular member formed to provide an annular oil discharge opening spaced from said inner tubular member.

6. An oil burner comprising, in combination, a hollow rotatably mounted shaft, an oil discharge pipe enclosed within said shaft and spaced therefrom, power means for rotating said shaft, forced air supply means, an atomizer mounted upon said shaft adjacent the discharge end of said oil discharge pipe, an air projector adapted to confine the forced air and terminating in a circular edge portion spaced from said atomizer to provide a circular air opening, said atomizer provided with an inner tubular member and an outer tubular member with an air passage therebetween, said outer tubular member being formed to provide an annular oil discharge opening spaced from said inner tubular member, whereby the forced air current is adapted to create an oil extracting air suction in advance of said atomizer, and also to create a current of air between said oil discharge pipe and said rotary shaft.

In testimony whereof I have signed my name to this specification.

HERMAN MILLER.
